UNITED STATES PATENT OFFICE.

HERBERT H. POHL AND ROY D. NEILL, OF MINNEAPOLIS, MINNESOTA.

FROST-PREVENTION DEVICE FOR WINDOWS.

Application filed February 18, 1925. Serial No. 9,945.

To all whom it may concern:

Be it known that we, HERBERT H. POHL and ROY D. NEILL, citizens of the United States, residing at Minneapolis, in the county of Hennepin and State of Minnesota, have invented certain new and useful Improvements in Frost-Prevention Devices for Windows, of which the following is a specification.

10 Our invention relates to frost prevention devices for windows. An object of the invention is to provide a device which may be readily applied to windows to prevent the formation of frost thereon or upon a portion thereof in cold weather. Our device is particularly applicable to windshields and other windows of motor vehicles, but may be applied to all windows where frost is liable to form and obscure the view, such 20 as display windows. We accomplish the objects of our invention by providing a device consisting of transparent material which is secured to the window in airtight spaced relation thereto so that a dead-air 25 space or pocket is produced.

The full objects and advantages of our invention will appear in connection with the detailed description thereof and the novel features of our inventive idea will be particularly pointed out in the claims.

In the accompanying drawings which illustrate a practical embodiment of our invention,—

Fig. 1 is an elevational view with the central portion broken away showing our invention applied to the windshield of a motor vehicle. Fig. 2 is a view in horizontal section. Fig. 3 is a view in horizontal section showing a slight modification. Fig. 4 is a view in horizontal section showing a further slight modification.

In the particular embodiment shown in Fig. 1 the device is applied to a windshield 10 which is supported by posts 12 and 14 in the usual manner. The device broadly considered consists of a piece of transparent material which is secured to the glass window in substantially airtight relation thereto and with its body portion spaced therefrom. We have found celluloid to be a material which is particularly adapted for such use and for illustrative purposes have shown a piece of sheet celluloid 16 whose edges are bent at right angles to form flanges 18 which are bent outwardly at right angles to form attaching flanges 20 lying

parallel to the body portion. These attaching flanges are secured to the glass window in substantially airtight relation. They may be secured by cementing or, as shown, 60 may be readily secured by strips of adhesive tape 22. The transparent sheets are preferably attached to the inside surface of the windows and may be of any desired size. As shown in Fig. 1 the sheet 16 is of such 65 size as to protect the portion of the windshield directly in front of the driver. If the transparent sheet is of such size as to require additional support, spacing means may be placed between the sheet and the 70 window. Fig. 3 shows a transparent sheet 16' provided with a ridge 24 adapted to rest upon the window. Fig. 4 shows a transparent sheet 16'' provided with two ribs 26 and 28 adapted to rest upon the window. 75

The operation and advantages of our invention will now be obvious. In cold weather the device can be readily attached to windows such as windshields and other windows of motor vehicles which are particularly liable to become coated with frost which obscures the vision therethrough. On account of the fact that the transparent material is secured to the window in spaced substantially airtight relation a dead-air 80 space is produced which prevents the formation of frost over the protected area. In the case of motor vehicles driving is made much easier and safer, and in the case of display windows, persons on the outside can 85 readily observe the objects on display on the inside. Celluloid is considered a particularly desirable material for our purpose, since it can be readily shaped between heated dies to produce the flanges and ribs, and furthermore this material is flexible and not easily cracked or broken.

We claim:

1. A frost prevention device for glass windows comprising a sheet of flexible 100 transparent material of different composition from that of said window, attaching flanges on the edges of said sheet for resting upon the surface of the window inside the edges thereof, and means of different composition from that of said window and sheet for removably securing said flanges to the window for producing a dead air space between the latter and said sheet. 105

2. A frost prevention device for glass 110 windows comprising a sheet of flexible transparent material of different composition

from that of said window, attaching flanges on the edges of said sheet for resting upon the surface of the window inside the edges thereof, means of different composition from 5 that of said window and sheet for removably securing said flange to the window for producing a dead air space between the

latter and said sheet, and a rib extending out from an intermediate portion of said sheet for resting against the window. ¹⁰

In testimony whereof we hereunto affix our signatures.

HERBERT H. POHL.
ROY D. NEILL.
